UNITED STATES PATENT OFFICE.

MAX HAEBERLEIN, OF NEW YORK, N. Y.

OIL-BRAKE FOR SPEED-GOVERNORS.

No. 860,913.

Specification of Letters Patent.

Patented July 23, 1907.

Application filed September 13, 1906. Serial No. 334,389.

To all whom it may concern:

Be it known that I, MAX HAEBERLEIN, a citizen of the Empire of Germany, residing in New York, in the borough of Manhattan, county and State of New York, have invented certain new and useful Improvements 5 in Oil-Brakes for Speed-Governors, of which the following is a specification.

This invention relates to certain improvements in the oil-brake for speed-governors for which Letters 10 Patent were granted to me on May 22, 1906, No. 821,359, the improvements being designed with a view of rendering the operation of the oil-brake more reliable in the different positions of the piston-rod.

In the oil-brake described in my prior patent, the 15 piston-rod is provided with longitudinal grooves which terminate within the edges of the bottom of the piston and which, by a certain tension imparted to the pressure-springs, control accurately the time during which the piston returns into its median position. When with 20 all motors whose velocity is controlled by a regulator with such an oil-brake the conditions which control the stability of regulation,—for instance, the fly-wheel capacity, the length of the pipe-connections and the velocity of the water at the water-wheels, were the 25 same, then, with a definite form of grooves and with a determined period of time for the return of the piston into its median position, could be obtained the best and most favorable regulation. Inasmuch, however, as in all motor-plants, and more especially in turbine- 30 plants, the fly-wheel capacity, length of pipe-conduits and velocity of water, are changeable within considerable limits, it would be necessary to obtain for each plant the proper form of the longitudinal grooves with 35 which the piston-rod has to be provided, so that by different openings for the oil and different periods of time which correspond to the special conditions, the return of the piston into its median position may be 40 obtained; but as it is impossible to determine in every special case for a good regulation the time required for the piston to return to its median position, and as the 45 accurate determination of the shape of the grooves would take up considerable time, it is useless to use one and the same shape for the grooves for all oil-brakes of this kind as thereby the proper change in the supply-openings for the oil could not be obtained in the proper manner.

The object of this invention is to obviate the objections stated and permit, by means of a very simple device, the proper changeability of the supply-openings 50 of the oil-brake; and for this purpose the invention consists in the improved regulation of the supply-openings in the oil-brake which will be fully described herein-after and finally pointed out in the claims.

In the accompanying drawings, Figure 1 represents 55 a vertical central section of a governor-mechanism in which my improved oil-brake is employed; Fig. 2 is a

horizontal section on line 2, 2, Fig. 1, and Figs. 3, 4, 5, 6 and 7 are details showing the different positions of the parts.

Similar letters of reference indicate corresponding 60 parts in the several figures.

Referring to the drawings, *a* represents the cylinder of my improved oil-brake and *d* the piston-rod, which is connected at its upper end with the lever of the speed-governor (not shown). The brake-cylinder *a* 65 is open at the upper end, its lower closed end being provided with an eye *a'* by which it is pivotally connected to a suitable standard. In the brake-cylinder *a* is fitted a piston *e*, through the bottom of which the piston-rod *d* is passed, the piston-rod being accurately 70 fitted into the central opening in said bottom. At each side of the bottom of the piston *e* is arranged a pressure-spring *f*, the springs being held in position between the inner and outer surfaces of the bottom by screw-nuts *g*, *g* that are held by jam-nuts *g'* on the 75 threaded portions of the piston-rod *d*, the tension of said springs being so adjusted by the screw-nuts *g* that they have always a tendency to force the piston *e* into a median position with respect to the piston-rod *d*. The springs *f* possess sufficient stiffness so as to impart 80 to the governor the required degree of stability. In the median position of the piston *e* the pressure of the springs on the piston-rod *d* is neutralized; but with every shifting of piston and piston-rod towards each other, they exert a resistance on the piston, which is 85 gradually increased from zero upwards.

In the piston-rod are arranged two longitudinal grooves *h* and *i* which are separated from each other by means of a narrow bridge *v*. In the bottom of the piston are arranged also two grooves *h'* and *i'*, between 90 which a narrow bridge *v'* of the same size as bridge *v* is formed. In the median position of the piston the two bridges *v*, *v'* are opposite to each other and prevent the flow of oil from the oil-chamber in the lower part of the cylinder *a* to the oil-chamber formed in the upper 95 part of the piston. When the piston is shifted for some distance in one or the opposite direction a connecting opening or channel corresponding in size to the extent of the shifting motion is formed between the two oil-spaces referred to, so that the play of the piston takes 100 place in the manner shown in my prior patent, No. 821,359. When, however, as shown in Figs. 3 and 4, the piston-rod *d* is turned on its axis for an angle of 180° it is obvious that as long as the bridge *v* moves along the central opening or bore in the bottom of the piston 105 no opening or channel between the two oil-spaces is obtained. The piston can therefore not be returned, after a shifting of the piston-rod, into its median position, or, at least, only with such diminished velocity as the oil can gradually leak through between piston 110 and piston-rod. When, however, as shown in Fig. 5, the piston-rod is turned only for a small angle, so that

the width of the connecting-opening or channel is reduced from w to w^1 , it is obvious that the oil-passages are reduced in the proportion of $\frac{w^1}{w}$, and that the time required for the return of the piston into its median position is enlarged in the proportion of $\frac{w}{w^1}$. It is therefore possible by a corresponding turning of the piston-rod to regulate the passage of the oil so as to permit different quantities of oil to pass, and consequently also to alter thereby the time in which the piston is returned to its median position. This turning of the piston-rod on its axis is accomplished by a hand-wheel on the piston-rod and a screw-connection with the socket on the pivot-eye of the same and can be done without dismantling any part of the oil-brake.

Instead of one pair of grooves on the piston-rod, several pairs can be arranged around the same, as shown in Figs. 6 and 7. By this arrangement the flow of the oil can be distributed around the piston-rod with facility.

Having thus described my invention, I claim as new and desire to secure by Letters Patent:

1. An oil-brake for speed-governors for motors, which consists of a brake-cylinder, a piston in said cylinder, a

piston-rod adapted to be connected with the governor and guided in the bottom of the piston, said piston-rod being provided with a pair of longitudinal grooves and a narrow bridge between said grooves, the bottom of the piston being also provided with a pair of grooves and a narrow bridge between the last pair of grooves, pressure-springs acting on opposite sides of the bottom of the piston, and means for turning the piston-rod so as to bring the grooves therein at different angles to the grooves on the piston-bottom.

35

2. An oil-brake for speed-governors for motors, which consists of a brake-cylinder, a piston in said cylinder, a piston-rod adapted to be connected with the governor and guided in a central opening in said piston-bottom, said piston-rod being provided with a pair of longitudinal grooves and a narrow bridge between said grooves, the bottom of the piston being also provided with grooves and a narrow bridge between said grooves, pressure-springs at opposite sides of the bottom of the piston, and means for turning the piston-rod on its axis so as to shift the position of the grooves on the piston-rod relatively to the grooves in the bottom of the piston.

40

In testimony, that I claim the foregoing as my invention, I have signed my name in presence of two subscribing witnesses.

MAX HAEBERLEIN.
